UNITED STATES PATENT OFFICE.

EDWIN F. PORTER, OF DORCHESTER, MASSACHUSETTS, ASSIGNOR OF TWO-THIRDS TO ARTHUR G. WELLMAN, OF WINCHESTER, AND WILLIAM H. BRYANT, OF REVERE, MASSACHUSETTS.

AMUSEMENT APPARATUS.

SPECIFICATION forming part of Letters Patent No. 716,755, dated December 23, 1902.

Application filed February 17, 1902. Serial No. 94,355. (No model.)

To all whom it may concern:

Be it known that I, EDWIN F. PORTER, a subject of the King of Great Britain, residing at Dorchester, in the county of Suffolk and State of Massachusetts, have invented new and useful Improvements in Amusement Apparatus, of which the following is a specification.

This invention relates to an amusement apparatus, and more especially to that class of amusement apparatus in which a series of cars or carriages of any desired shape and design are supported upon a rotary carrier-frame and each car supplied with means for applying power in order that the same may be rotated together with said carrier-frame.

The object of the invention is to provide, in an apparatus of the character described, a strong, durable, and safe apparatus in which the cars or carriages not only are supplied with means by which the riders may propel the same in a circular path, but are also so constructed that they may be swung outwardly from said carrier-frame center by centrifugal force as the carrier-frame increases its speed of rotation. By graduating the speed of the motor the occupants of the car may vary the path of said car from a perfect circle to a curvilinear path, and thus impart variety to the amusement and produce somewhat the sensation of flying experienced in flying through the air.

The invention consists, in an apparatus of the character described, of a carrier-frame arranged to rotate in a horizontal plane, a swinging frame pivotally suspended from beneath said carrier-frame in such a manner as to swing radially outward therefrom, a car fast to said swinging frame, a motor carried by said car, and a cylindrical platform located inside the path of rotation of and arranged to contact with said car and forming a braking means.

The invention again consists in certain novel means for stopping and locking the car in a fixed position to said platform.

The invention again consists in the instrumentalities set forth, in combination with a fence located upon and extending around

said platform and a gate in said fence, said gate constituting a switch arranged to make and break an electric circuit operatively connected with the motor in the car; and, further, the invention consists in attaching to said gate a hooked stop which is so arranged as to engage and lock the car in a fixed position when the gate is open and the circuit broken.

The invention finally consists in the combination and arrangement of parts set forth in the following specification and particularly pointed out in the claims thereof.

Referring to the drawings, Figure 1 is a front elevation of my improved amusement apparatus, the same being shown as constructed with four cars; but this number may be increased or diminished without departing from the spirit of my invention. Fig. 2 is a detail plan of the platform of the apparatus, together with the four cars, showing said cars locked in position and the gates upon the four main supports of the framework being shown open. Fig. 3 is an enlarged detailed plan of one of the cars, together with a portion of the platform and the fence surrounding said platform, with one of the gates shown open and the means connected to said gate locking the car in position. Fig. 4 is a diagram view of the electrical connections whereby power is supplied to an electric motor carried by said car. Fig. 5 is a plan view, upon a reduced scale, of the carrier-frame shown in Fig. 1.

Like numerals refer to like parts throughout the several views of the drawings.

In the drawings, 10 is a vertical framework, preferably constructed of angle-iron corner-supports 11 11, joined together by braces 12 12 and having a horizontal platform 13 surrounding the same and provided with stairways 14 14, by which said platform is reached from the ground. In the center of the frame 10 is provided a vertical shaft 15, which is arranged to rotate in bearings 16 16 and in a pedestal-bearing 17. The bearings 16 16 are preferably roller-bearings and the pedestal-bearing 17 a ball-bearing to reduce the friction.

A carrier-frame 18 is fastened to the upper

end of the shaft 15. Said carrier-frame is preferably constructed of iron or steel and is cylindrical, provided with an annular flange 19, and being strengthened and rendered perfectly firm by stay-rods 20. The swinging frames 21 are pivotally supported upon the flange 19 of said carrier-frame, as shown in Fig. 1. The said swinging frames 21 are preferably constructed of two wire ropes, cables, or rods 22, which cross each other diagonally and are joined together at the crossing-point by a fastening 23 of any desired construction. The upper ends of the rods 22 are each formed with an eye 24, said eyes being supported in staples 25, fast to the flange 19. It will be noted that the staples 25 are equidistant from the center of the carrier-frame 18 and that they are so arranged and located with relation to the eyes 24 that while said swinging frames can swing outwardly from their normal position (shown in Fig. 1)—viz., in a vertical plane tangential to said carrier-frame, as shown in dotted lines—said frames cannot swing tangentially to said carrier-frame, being supported upon their upper ends upon the staples 25 at two points a considerable distance apart. Each of the swinging frames 21 has a car or carriage 26, rigidly fastened thereto by supporting-braces 27. The cars 26 are each provided with an electric motor 28, which imparts a rotary motion to a fan-propelling wheel 29. Said motor is electrically connected through the swinging frames 21, carrier-frame 18, and framework 10 to a dynamo or other source of electric power, as hereinbefore described. The motors 28 are arranged to be operated by an attendant from the platform 13, and the rapid rotation imparted by said electric motors to the propellers 29 forces the several cars in a curvilinear path in the direction of the arrow, Fig. 2. Normally, as hereinbefore set forth, the swinging frames 21 will hang suspended in a vertical plane tangential to the carrier-frame 18; but as the speed of rotation of the carrier-frame increases the swinging frames and the cars carried thereby will be swung outward radially from the center of said carrier-frame to the position shown by dotted lines in Fig. 1. When the motors are slowed up by shutting off the current, the cars, together with the swinging frames, will descend to the position shown in full lines, Fig. 1, the sides of said cars coming in contact with the periphery of the platform 13, which will assist in stopping the cars through friction with the periphery of said platform, and, moreover, at each of the points where it is desired that the car should stop a slight projection 30 is provided with inclined ends 31 and preferably covered with leather 32 to increase the friction between said platform and the side of said car.

Around the platform 13, near the periphery thereof, is provided a fence 33. Said fence is provided with rotary gates 34, one gate being provided for each car. Said gates

are fast to a rotary shaft 35, which projects beneath the platform 13 and has fastened thereto a hooked stop-arm 36, arranged to engage an arm 37, rigidly fastened to the car and provided with a hole 38, through which said hooked arm projects when the car is in the proper position, and thus positively locks said car in position when the gate is open. This gate and lock form a safety device, and as an additional means of safety each of the gates is in electric circuit with the wires connecting the different motors to the dynamo and constitute switches so arranged that when the gates are open, or any of them, the electric circuit is broken and when all are closed the electric circuit is made.

The wires forming the electric circuit are illustrated in diagram in Fig. 4, in which the wire 39 passes from the dynamo or battery through a brush 40 to the shaft 15 and thence through the carrier-frame 18, swinging frame 21, and wire 47 to the motor 28, returning through the wire 41, brush 42, wire 43, wire 44, and through the different switches 45, formed by the gates, as hereinbefore described, and wire 46 to the battery or dynamo through which the circuit is completed. Any desired form of switch may be introduced in the electric circuit to make or break the same independent of the switches 45.

The general operation of my improved amusement apparatus is as follows: Assuming the cars to be in the position shown in Figs. 1 and 2 and the occupants seated therein, an attendant closes each of the gates 34, thus withdrawing the hooked arm 36 from the hole 38 in the arm 37 upon the car 26 and completing the electric circuit by means of the switches 45, operated by said gates. The apparatus is now in condition to be started. The attendant completes the circuit with the switch provided for the purpose. The motor rotates the fan-wheels 29, and the cars, together with the carrier-frame 18, are rotated in the direction of the arrow, Fig. 2. As the speed increases the cars and the swinging frames 21 swing outwardly from the action of centrifugal force, and as the current is shut off and the motors stop said cars gradually come to the position shown in Fig. 1, the sides of the cars engaging the incline 31 upon the projections 30, fast to the periphery of the platform 13. As the car approaches the position shown in Figs. 2 and 3, the attendants throw the gates open and the hooked arm engages the arm 37 upon each of the cars, thus holding and locking the cars in position while the occupants alight therefrom and new occupants enter.

It is an important feature of my invention that the platform from which the occupant enters the car should be raised above the height of a man's head, and also the cars should be raised so that the lowest portion of the propeller 29 shall not strike any person passing beneath the car. It is rendered especially necessary, on account of the safety

of the public, that this feature should be incorporated in apparatus of the nature hereinbefore described, as it is evident that if the cars were placed near the ground, so that 5 people could step into them, the same would constitute an element of danger, as the cars swing out more or less, as hereinbefore described, owing to centrifugal force. It is therefore a necessity that the cars should be 10 raised above the height of a man's head, so that they may pass over people standing upon the ground without causing any injury, and in order to do this I have provided a raised platform 13, so that people may pass under the 15 platform and up the stairway 14 through the opening in the platform, and thus be brought to a height sufficient to step from the platform into the car.

It is evident that the hooked arm for locking the car in a stationary position might be placed upon the car and a fixed arm 37 placed upon the platform or its supports without departing from the spirit of my invention.

Having thus described my invention, what 25 I claim, and desire by Letters Patent to secure, is—

1. In an apparatus of the character described, a carrier-frame arranged to rotate in a horizontal plane, a swinging frame pivotally suspended from beneath said carrier-frame in such a manner as to swing radially outward therefrom, a car fast to said swinging frame, means to prevent said swinging frame from swinging tangentially in relation 35 to said carrier-frame, a motor carried by said car, a stationary platform located inside the path of rotation of said car, and a stop located upon said platform, near the periphery thereof, and arranged to engage said car and lock 40 the same to said stationary platform.

2. In an apparatus of the character described, a carrier-frame arranged to rotate in a horizontal plane, a swinging frame pivotally suspended from beneath said carrier-frame in such a manner as to swing radially outward therefrom, a car fast to said swinging frame, means to prevent said swinging frame from swinging tangentially in relation to said carrier-frame, a motor carried by said 50 car, a stationary platform located inside the path of rotation of said car, and a stop pivoted upon said platform, near the periphery thereof, and arranged to engage said car and lock the same to said stationary platform.

55 3. In an apparatus of the character described, a carrier-frame arranged to rotate in a horizontal plane, a swinging frame pivotally suspended from beneath said carrier-frame in such a manner as to swing radially outward therefrom, a car fast to said swinging frame, means to prevent said swinging frame from swinging tangentially in relation to said carrier-frame, a motor carried by said car, a stationary platform located inside the 60 path of rotation of said car, and a hooked stop pivoted to said platform, near the periphery

thereof, and arranged to engage said car and lock the same to said stationary platform.

4. In an apparatus of the character described, a carrier-frame arranged to rotate in a horizontal plane, a swinging frame pivotally suspended from beneath said carrier-frame in such a manner as to swing radially outward therefrom, a car fast to said swinging frame, means to prevent said swinging frame from swinging tangentially in relation to said carrier-frame, a motor carried by said car, a stationary platform located inside the path of rotation of said car, a fence located upon the top of said platform and extending 75 therearound, a rotary gate in said fence, and a hooked stop pivoted to said platform, near the periphery thereof, and operated by said gate to engage said car and lock the same to said stationary platform. 83

5. In an apparatus of the character described, a carrier-frame arranged to rotate in a horizontal plane, a car pivotally suspended from beneath said carrier-frame in such a manner as to swing radially outward therefrom, means to prevent said car from swinging tangentially in relation to said carrier-frame, a motor carried by said car in electric circuit with a source of power, a platform located inside the path of rotation of said car, 95 a fence located upon the top of said platform and extending therearound, a gate in said fence, said gate constituting a switch in said circuit and arranged to break said circuit when open, and to make said circuit when 100 closed.

6. In an apparatus of the character described, a carrier-frame arranged to rotate in a horizontal plane, a car pivotally suspended from beneath said carrier-frame in such a 105 manner as to swing radially outward therefrom, means to prevent said car from swinging tangentially in relation to said carrier-frame, a motor carried by said car in electric circuit with a source of power, a platform 110 located inside the path of rotation of said car, a fence located upon the top of said platform and extending therearound, a gate in said fence, said gate constituting a switch in said circuit and arranged to break said circuit 115 when open and to make said circuit when closed, and a hooked stop connected to and rotated by said gate and arranged to engage and lock said car in a fixed position.

7. In an apparatus of the character described, a carrier-frame arranged to rotate in a horizontal plane, a swinging frame pivotally suspended from beneath said carrier-frame in such a manner as to swing radially outward therefrom, a car fast to said swinging frame, means to prevent said swinging frame from swinging tangentially in relation to said carrier-frame, a motor carried by said car, a cylindrical platform located inside the path of rotation of said car and arranged to 120 contact with said car, and frictional projections fast to the periphery of said platform 125 130

and constituting a braking means whereby said car is brought to a stationary position.

8. In an apparatus of the character described, a carrier-frame arranged to rotate in a horizontal plane, a swinging frame pivotally suspended from beneath said carrier-frame in such a manner as to swing radially outward therefrom, a car fast to said swinging frame, a motor carried by said car, and a cylindrical platform located inside the path of rotation of and arranged to contact with said car and forming a braking means.
9. In an apparatus of the character described, a carrier-frame arranged to rotate in a horizontal plane, a swinging frame pivotally suspended from beneath said carrier-frame in such a manner as to swing radially outward therefrom, a car fast to said swinging frame, a motor carried by said car, a stationary platform located inside the path of rotation of said car, a stop located upon said platform, near the periphery thereof, and arranged to engage said car and lock the same to said stationary platform.

10. In an apparatus of the character described, a carrier-frame arranged to rotate in a horizontal plane, a swinging frame pivotally suspended from beneath said carrier-frame in such a manner as to swing radially outward therefrom, a car fast to said swinging frame, a motor carried by said car, a stationary platform located inside the path of rotation of said car, a stop pivoted upon said platform, near the periphery thereof, and arranged to engage said car and lock the same to said stationary platform.

11. In an apparatus of the character described, a carrier-frame arranged to rotate in a horizontal plane, a swinging frame pivotally suspended from beneath said carrier-frame in such a manner as to swing radially outward therefrom, a car fast to said swinging frame, a motor carried by said car, a stationary platform located inside the path of rotation of said car, and a hooked stop pivoted to said platform, near the periphery thereof, and arranged to engage said car and lock the same to said stationary platform.

12. In an apparatus of the character described, a carrier-frame arranged to rotate in a horizontal plane, a swinging frame pivotally suspended from beneath said carrier-frame in such a manner as to swing radially outward therefrom, a car fast to said swinging frame, a motor carried by said car, a plat-

form located inside the path of rotation of said car, a fence extending around said platform, a rotary gate, and a hooked stop connected to and rotated by said gate and arranged to engage and lock said bar in a fixed position.

13. In an apparatus of the character described, a carrier-frame arranged to rotate in a horizontal plane, a car pivotally suspended from beneath said carrier-frame in such a manner as to swing radially outward therefrom, a motor carried by said car in electric circuit with a source of power, a platform located inside the path of rotation of said car, a fence extending around said platform, a gate in said fence, said gate constituting a switch in said circuit and arranged to break said circuit when open, and to make said circuit when closed.

14. In an apparatus of the character described, a carrier-frame arranged to rotate in a horizontal plane, a car pivotally suspended from beneath said carrier-frame in such a manner as to swing radially outward therefrom, a motor carried by said car in electric circuit with a source of power, a platform located inside the path of rotation of said car, a fence extending around said platform, a gate in said fence, said gate constituting a switch in said circuit and arranged to break said circuit when open and to make said circuit when closed, and a hooked stop connected to and rotated by said gate and arranged to engage and lock said car in a fixed position.

15. In an apparatus of the character described, a carrier-frame arranged to rotate in a horizontal plane, a swinging frame pivotally suspended from beneath said carrier-frame in such a manner as to swing radially outward therefrom, a car fast to said swinging frame, a motor carried by said car, a cylindrical platform located inside the path of rotation of said car arranged to contact with said car, and frictional projections fast to the periphery of said platform and constituting a braking means whereby said car is brought to a stationary position.

In testimony whereof I have hereunto set my hand in presence of two subscribing witnesses.

EDWIN F. PORTER.
